FENCE CHARGING DEVICE

Charles Gallot and Albert Alpaugh, Milwaukee,
Wis.

Application July 9, 1937, Serial No. 152,704

18 Claims. (Cl. 175—373)

This invention relates primarily to charging devices for electric fences, although certain features thereof are also applicable to other uses.

It has been found that a fence carrying a shock-producing electric charge provides an effective and reliable barrier for cattle and other livestock, and that such a fence may be erected most economically, since a single wire, properly charged, may alone be relied upon to confine the stock. It has also been found that brief, high-potential charges, recurring at spaced intervals, renders the fence quite effective without subjecting the animals to the danger of electrocution which might otherwise result from a continuous charge.

We have also found that the duration of each charge may be reduced to a substantially irreducible minimum without impairing the effectiveness of the fence, thereby permitting a substantial reduction in the electric energy consumed.

One object of the present invention is to improve the construction, operation and reliability of charging devices for electric fences and the like.

Another object is to provide an improved device for the intermittent charging of electric fences which shall be proof against maintaining a charge of death-producing duration.

Another object is to provide an electric charging device which will reliably function to produce intermittent electric charges of minimum duration.

Another object is to provide a battery fed electric charging device capable of producing intermittent high potential charges over long periods of time.

Another object is to provide improved means for energizing and controlling a battery fed transformer.

Other objects and advantages will appear, expressed or implied, from the following description of an electric charging device embodying the present invention.

In the accompanying drawing—

Figure 1 is a diagrammatic view of an electric fence charger constructed in accordance with the present invention.

Fig. 2 is a sectional view on the line 2—2 of Fig. 1.

The charging device selected for illustration is controlled by a reciprocating member intermittently driven in one direction by a power actuated impeller which, in turn, is rendered active by each return movement of the member in the opposite direction.

The reciprocating member shown comprises a ball 10 mounted to roll freely up and down an inclined track, preferably formed by a pair of fixed parallel rods 11, upon which the ball is loosely confined by a similar pair of rods 12 above it.

The power actuated impeller shown comprises a lever 13, rockably supported at one end upon a stationary fulcrum pin 14, and having a driving head 15, preferably of rubber, at its opposite end. The head 15 is disposed adjacent the lower end of the track within the range of movement of the ball 10. The lever 13 is yieldably retained in retracted position, preferably against an adjustable stop screw 16, by an appropriate spring 17, and is actuated in a manner to drive the ball upwardly along its track 11 by any appropriate power means, such as an electromagnet 18.

In this instance, the electromagnet 18 is energized by a battery 19 or other source of electrical energy through an appropriate circuit 20 controlled primarily by a normally open switch, including contacts 21 and 22, which is momentarily closed by each return movement of the ball 10 downwardly along its track 11. Contact member 21 is shown mounted upon and insulated from the lever 13, and the coacting contact 22 is shown carried by a resilient arm 23 having its lower end fixed to and insulated from the lever 13 and its upper free end projecting into the path of movement of the ball 10 in advance of the driving head 15 of the lever.

The arrangement is such that upon each return movement of the ball 10 down its track 11, the arm 23 is flexed by impact of the ball to close the circuit 20 through the contacts 21 and 22 and thereby energize the electromagnet 18. When this occurs, the lever 13 is actuated by the electromagnet to effect a power stroke, causing the head 15 thereof to deliver a driving impulse to the ball, and thereby causing the ball to roll up its inclined track a distance dependent upon the effectiveness of the stroke. It will of course be understood that the instant the ball leaves the head 15, the contacts 21 and 22 separate, the electromagnet is de-energized, and the lever 13 returns to the retracted position shown where it remains until the contacts 21 and 22 are again closed by impact of the ball 10 on its return stroke.

The duration of each operating cycle is of course determined by the distance traveled by the ball 10 which may be regulated in various ways. In the device shown for instance this may be regulated by varying the length and therefore the

effectiveness of the power stroke of the lever 13 by regulating the stop screw 16.

The resilient arm 23, carrying contact 22, is preferably of such stiffness as to avoid making contact between the members 22 and 24 by the mere weight of the ball 10, such contact being possible only by impact of the moving ball as it travels down the incline. It is thus possible for the device to remain at rest with the ball resting idly against the arm 23. This of course avoids any possibility of stalling with the electric circuit closed.

The device thus far described may be applied to various uses, but the quick substantially instantaneous power strokes of the impeller 18 at recurring intervals may be utilized to particular advantage in the charging of electric fences in a manner which will now be described.

The fence charging system shown includes a variable strength, step-up transformer whose secondary high-potential coil 25 is connected through an appropriate lead 26 to a fence (not shown) and whose primary low-potential coil 27 is connected to an appropriate source of electric energy, such as the battery 19, through a switch controlled circuit 28. When energized by the same battery, the circuit 28 is preferably connected in parallel with the circuit 20. The strength of the transformer may in this instance be regulated by a hand switch 29 which is moveable to cut out a portion 27' of the primary coil through a lead 30.

The circuit 28 is preferably controlled by a switch of novel construction actuated and controlled by the lever 13. This switch includes a contact 31 carried by a relatively stiff arm 32, fixed to and insulated from the lever 13 so as to swing therewith, and arranged to strike a co-acting contact 34 as the lever 13 approaches the end of its power stroke. The contact 34 is carried by the free end of a resilient arm 35 fixed at its other end to a stationary support 36, the resiliency of the arm 35 being such that the impact of the contact 31 against the contact 34 causes the latter to vibrate at high frequency and low amplitude, thereby setting up high frequency fluctuations in the primary circuit 28 of the transformer which are particularly effective in causing the transformer to set up a very high potential in the fence charging line 26.

It has been found that with a vibratory switch of the type described, the transformer is capable of delivering potentials as high as thirty thousand volts from a battery supply of only six volts. The best results have been obtained when the contacts 31 and 34 are of soft silver and when the arm 35 is of phosphor bronze.

It will thus be noted that a device has been provided capable of delivering to a fence, at desired intervals, a succession of electric charges at very high potential and of practically microscopic duration, the charging circuit being closed, through the contacts 31 and 34, only while the lever 13 is at the end of its power stroke, it being understood of course that the entire forward and return stroke of the lever consumes but an instant of time.

Various changes may be made in the embodiments of the invention above specifically described without departing from or sacrificing the advantages of the invention as defined in the appended claims.

We claim:

1. In a charger for an electric circuit the combination of a reciprocable member, a striker for successively driving said member in one direction, means controlled by successive movements of

said member in an opposite direction for actuating said striker, and means including a second member moveable by and with said striker for intermittently charging a circuit.

2. In a charger for an electric circuit the combination of a guide, a member moveable back and forth along said guide, a striker for successively driving said member in one direction along said guide, means controlled by successive movements of said member in the opposite direction along said guide for actuating said striker, and means including a second member moveable by and with said striker for intermittently charging a circuit.

3. In an intermittent charger for an electric circuit the combination of a reciprocable inertia member, a moveable striker for intermittently driving said member, means controlled by movement of said member in the opposite direction for actuating said striker, and circuit charging means including a switch controlled by the position of said striker.

4. In an intermittent charger for an electric circuit the combination of a reciprocable member, a moveable impeller for intermittently driving said member, means controlled by movement of said member for causing said impeller to execute a driving stroke, and a normally open switch responsive to movement of said impeller and momentarily closed at the end of said driving stroke.

5. In an intermittent electric charger the combination of a reciprocable member, an electrical transformer, and power actuated means including a reciprocable striker controlled by movement of said member for intermittently driving said member, and means controlled by said striker independently of said member for controlling said transformer.

6. In an intermittent electric charger the combination of a reciprocable inertia member, an electrical transformer, a power actuated impeller controlled by movement of said member for intermittently driving said member, and means including a switch controlled by said impeller for intermittently energizing said transformer.

7. In an intermittent charger, the combination of a transformer having a secondary coil and a primary coil, a reciprocable member, a power actuated striker controlled by movement of said member for intermittently driving said member, and means including a switch controlled by said striker for intermittently energizing said primary coil.

8. In an intermittent charger, the combination of a transformer having a secondary coil and a primary coil, normally open switch means closeable to connect said primary coil with a source of electrical energy, a reciprocating member, and power actuated means including a reciprocable striker controlled by movement of said member for intermittently driving said member and for intermittently closing said switch.

9. In an intermittent charger the combination of a transformer having a secondary coil and a primary coil, a normally open switch closeable to connect said primary coil with a source of electrical energy, said switch including a vibratory contact set into vibration by closing of said switch, a reciprocating member, and reciprocable power actuated means controlled by movement of said member for intermittently driving said member and for intermittently closing said switch.

10. In an intermittent electric charger the combination of a transformer, means including a switch closeable to energize said transformer,

said switch having a vibratory contact set into vibration by the closing of said switch, and power actuated means for intermittently closing said switch.

5 11. In an intermittent charger for an electric circuit, the combination of a transformer having primary and secondary coils, means including a switch closeable to energize said primary coil, said switch including a contact mounted to vibrate when closed to thereby set up high frequency fluctuations in said primary coil, and power actuated means for intermittently closing said switch.

10 12. In a device of the character described the combination of a guide, a ball adapted to roll back and forth along said guide, a striker element arranged to drive said ball in one direction along said guide, and means including an element non-responsive to the static weight of said ball but moveable in response to impact of said ball thereagainst for actuating said striker.

15 13. In a device of the character described, the combination of a guide, a ball adapted to roll back and forth along said guide, a striker disposed at one end of said guide for driving said ball in one direction along said guide, an electromagnet for actuating said driver, and switch means non-responsive to the static weight of said ball but actuated by impact of said ball thereagainst for energizing said electromagnet.

20 14. In a device of the character described, the combination of a reciprocable member, an inclined guide therefor, a striker disposed adjacent the lower end of said guide for driving said member upward along said guide, an electromagnet for actuating said striker, switch means for controlling said electromagnet, and an element non-responsive to the static weight of said member but actuated by impact of said member there-

25 40 against for momentarily closing said switch.

15. In a device of the character described the combination of a reciprocating inertia member, a reciprocable driver therefor, means controlled by movement of said member in one direction for effecting a driving and return stroke of said driver in a manner to drive said member in an opposite direction, and an electric circuit controlled by movement of said driver.

16. In a device of the character described the combination of a reciprocable striker, actuating means therefor operable to effect a driving and return stroke of said striker, an electric circuit controlled by said striker, a reciprocable inertia member intermittently driven by said striker, and means controlled by said member for controlling said actuating means to thereby control the frequency of operation of said striker.

17. In a device of the character described the combination of a reciprocable striker, actuating means therefor operable to effect a driving and return stroke of said striker, an electric circuit, means controlled by said striker for closing said circuit for a predetermined momentary time interval, a reciprocable inertia member intermittently driven by said striker, and means controlled by said member for controlling said actuating means to thereby control the frequency of closing of said circuit.

18. In an intermittent charger, the combination of a transformer having a secondary coil and a primary coil, a reciprocable inertia member, power actuated means controlled by said member for actuating the same, and means controlled by said last named means for intermittently energizing said primary coil and for setting up high frequency fluctuations therein during each period of energization thereof.
